Fig. 3.

UNITED STATES PATENT OFFICE.

OSCAR WOODWARD, OF BABYLON, NEW YORK, ASSIGNOR TO REMINGTON TYPEWRITER COMPANY, OF ILION, NEW YORK, A CORPORATION OF NEW YORK.

TYPEWRITING-MACHINE.

1,342,490.

Specification of Letters Patent.

Patented June 8, 1920.

Application filed April 10, 1919. Serial No. 288,957.

To all whom it may concern:

Be it known that I, OSCAR WOODWARD, a citizen of the United States, and resident of Babylon, in the county of Suffolk and State of New York, have invented certain new and useful Improvements in Typewriting Machines, of which the following is a specification.

My invention relates to typewriting machines and more particularly to means for controlling the carriage of a typewriting machine.

In typewriting machines where the paper is carried by the carriage said carriage usually steps toward the left in the operation of writing, and it is withdrawn toward the right to begin a new line; although in some machines the directions of the motions are the opposites of those stated. When the carriage is withdrawn toward the right it is commonly arrested by a stop such, for example, as a margin stop, and it is the intention of said stop to have the next line of writing begin at a definite letter space position. Due to various causes, however, the carriage escapement mechanism sometimes does not resume control of the carriage correctly with the result that the next line of writing is begun a letter space to the right of the intended position, resulting in an uneven margin at the left-hand side of the typewritten page. There are also other instances where the carriage makes a false step when it is restored to the control of the escapement.

The principal purpose of my invention is to provide an improved means for overcoming the liability of the carriage to make a false step as above mentioned.

My invention may be regarded in part as an improvement on that set forth in the application of George A. Seib, filed December 6, 1918, Sr. No. 265,512.

To the above ends my invention consists in certain features of construction and combinations and arrangements of parts, all of which will be fully set forth herein and particularly pointed out in the claims.

In the accompanying drawings, in which my invention is shown embodied in a Remington typewriter,—

Figure 1 is a fragmentary rear elevation partly in section.

Fig. 2 is a side elevation partly in section.

Fig. 3 is a plan view showing the parts in 55 the position they occupy when the carriage is returning or moving toward the right.

Fig. 4 is a view similar to Fig. 3 but with some parts omitted and showing the mechanism in the position it occupies when the 60 carriage is moving toward the left.

Fig. 5 is an enlarged perspective view of the principal parts of my improvements.

Fig. 6 is a vertical cross-section of a 65 modification.

In all of the figures, except Fig. 2, the mechanism is shown as viewed from the rear.

In the drawings, 1 represents the top plate of a Remington typewriter, 2 the carriage 70 feed rack, 3 the feed pinion, and 4 the escapement wheel of that machine. Said escapement wheel is fixedly mounted by means of set screws 5 on the rear end of a shaft 6 which is journaled at its ends in a 75 bracket 7 secured by screws 8 to the top plate 1. The pinion 3 is rigid on or integral with a sleeve 10 journaled on the shaft 6 and having at its rear end a drum 11 which is formed with internal ratchet 80 teeth adapted to be engaged by a pawl mounted on the front face of the escapement wheel 4. The construction of said pawl and ratchet mechanism is such that the carriage cannot be moved toward the left while the 85 rack 2 is in engagement with the pinion 3 except by turning the escapement wheel 4 but said carriage can be withdrawn toward the right without turning said wheel. The feed mechanism thus far described is or may 90 be like that shown in the patent to Barney, No. 1,247,616, dated November 27, 1917. A drum 12 which is secured to a part of the bracket 7, is shown in the drawing but this drum is associated with back spacing mechanism, not shown. The Remington carriage is drawn toward the operator's left by means of a spring drum 14 which is connected to the carriage by a tape 15.

The feed dog mechanism comprises a dog 100 rocker 16 pivoted on two cone pivots 17 mounted in a bracket depending from the top plate 1, and having an adjustable arm 18 connected with the universal bar and space key of the machine. The dog rocker has a 105 rear, beveled, fixed dog 20 and a stepping dog 21, the latter pivoted at 22 and adapted to vibrate between stops 23 and 24, a spring

25 tending to throw said dog toward the right in Fig. 1 against the stop 24 but said dog being normally held by the pressure of the carriage spring, through escapement 5 wheel 4, against the stop 23, as shown.

There are certain operations of the machine which result in the dog 21 getting misplaced with reference to the lowermost tooth of the escapement wheel 4. For example, if the carriage is stepped down to the left until it is arrested by a stop there is no longer anything to turn the wheel 4 because the carriage can move no farther. If then the space key or a character key is operated and the rocker 16 is thereby vibrated, the dog 21 will move out of engagement with the escapement wheel and will be thrown back by the spring 25 against the stop 24, and when the rocker comes back to its normal position this dog will come in behind the lowermost tooth of the wheel instead of in front of it as it should be. That is to say, it will stand at the right of said tooth in Fig. 1 instead of at the left of it. If now the feed rack be raised out of the pinion 3 and the carriage be drawn back to the operator's right until it is arrested by the margin stop and the rack then restored to engagement with the pinion 3, the wheel 30 4 will be free to make substantially an entire step after the rack comes into engagement with the pinion, and the carriage will not stand in the position intended. For example, if the margin stop was set to begin a new line of writing at the point 10 on the carriage scale it will under these conditions drop down to point 11 before being arrested by the escapement mechanism. A similar thing would happen if the carriage was drawn back without raising the rack. There are various other conditions under which this or similar errors can arise. It has heretofore been proposed to place in the escapement mechanism a third dog sometimes 45 called a "margin dog" to hold the escapement wheel 4 in case of a false operation whereby the stepping dog is displaced as above described. Such a margin dog is shown in my prior application filed Sept. 3, 1918, Sr. No. 252,377. The margin dog shown in said application is effectual to prevent the error above described but it is mounted on the dog rocker and it vibrates into and out of the escapement wheel at the same time as the 50 two escapement dogs, and it has been found that in very rapid operation it is preferable that the margin dog be not so mounted as to vibrate with the escapement dogs but that during the operation of writing it be held 55 out of action. A margin dog so held out is shown in the application of George A. Seib hereinbefore referred to. My invention is an improvement on that set forth in said Seib application, and includes a margin dog 60 65 26 and a detent or dog 27, both adapted to

engage the lowermost tooth of the escapement wheel, as clearly shown in Figs. 3 and 5, the former engaging the face of said tooth and the latter the back of said tooth, so that the two dogs together can hold said tooth 70 and escapement wheel against any turning motion at all, when both are in engagement therewith. To this end the body of the wheel is cut away so as to form each tooth with a back portion parallel with its face 75 preferably above the end of the tooth which is engaged by the escapement dogs 20, 21, all as shown in Fig. 1.

The detent dog 27 consists of an arm of sheet metal pivoted on a stud screw 28 which 80 at its lower end is screwed into a base plate 30, which is secured to the top plate 1 by screws 31 passing through slots in said base plate so as to allow of adjustment of the mechanism toward and from the escapement 85 wheel. The pivot screw 28 is elongated upward and the dog 27 is bent to form a vertical yoke piece 32 and again to form a horizontal ear 29 which is pivoted on the screw 28 near the top thereof so that the dog 27 has pivotal bearing on the screw at two points widely separated, whereby said dog is accurately guided in its vibratory movements. This dog normally occupies the position shown in the drawings, and it clicks in behind each escapement wheel tooth that passes it.

The margin dog 26 is also pivoted on the screw 28 beneath and above the dog 27, said margin dog being so shaped and bent as 100 to include a vertical yoke-piece 33 and a long horizontal arm 34, the latter of which is pivoted on the screw 28 at the top thereof. As here shown the yoke-piece 33 is a little longer than the yoke-piece 32 so that the 105 two folds of the dog 27 are included between the two folds of the dog 26 where said dogs are pivoted on the screw. A spring 35 coiled about the screw 28 is under torsional stress and at one end is connected with the dog 27 and at the other end with the dog 26 so that said spring acts on both dogs at once and tends to move the detent dog 27 toward the front of the machine and the margin dog 26 toward the rear of the machine. Preferably said detent dog is situated back of the wheel 4 and the margin dog is situated in front of said wheel, hence the tendency of the spring is to move both dogs into engagement with the wheel.

The arm 34 extends forward beneath the feed rack 2 and it has mounted thereon a T-shaped piece of spring-steel including an arm or shank 36 which is secured to the top of the bar 34 and a shoe 37 pressed upward 125 by the resilience of the arm 36 into frictional engagement with the toothed under edge of the rack 2. This engagement occurs however only when said rack 2 is in normal position in engagement with the pinion 3. 130

When said rack is raised out of engagement with said pinion the shoe 37 does not follow it upward to the full extent of its motion and the rack therefore moves out of contact with the shoe. The construction is such that when the carriage is moving toward the left, that is to say, toward the right as viewed in the drawings and as indicated by the arrow in Fig. 4, the friction of the rack 2 on the shoe 37 tends to swing the dog 26 out of engagement with the escapement wheel 4 to the position shown in Fig. 4, and against the pressure of the spring 35. Said spring is so designed and regulated that its pressure is not sufficient to overcome the frictional tendency of the arm 36, so that during the operation of writing the dog 26 is held out of action, that is to say, out of engagement with the escapement wheel, as shown in Fig. 4.

When, however, the rack 2 is raised to move the carriage in either direction the spring 35 immediately brings the margin dog 26 into action and it is maintained in engagement with the wheel after the rack is restored and until moved out of engagement as hereinafter described. Furthermore if the carriage be moved toward the operator's right, that is to say, toward the left in the drawings, as indicated by the arrow in Fig. 3, then the friction on the shoe 37 does not prevent the spring 35 from moving the margin dog into engagement with the escapement wheel.

The arm 36 is secured to the arm 34 by screws 38. In order to prevent the flexure of the arm 36 from coming at the point where one of these screws passes through it, which of course would be the weakest point of the arm, I have provided a guard 40 consisting of a strip of sheet metal lying on top of the arm 36 and bent upward at an inclination at 41; and the screws 38 clamp the spring arm 36 between the arm 34 and guard 40. It results from this construction that the flexure of the arms 26 comes chiefly at the point where said arm emerges from under the bend 41 so that said arm 36 is much less likely to be broken or weakened by repeated flexure and recovery. By using screws at 38 instead of rivets, the shoe 37 can easily be replaced with a new one at any time.

Instead of having the shoe engage directly with the rack teeth it may with like results engage with a plain untoothed bar attached to any suitable part of the carriage or to the rack and extending down slightly beyond the points of the rack teeth, as shown at 2^b at Fig. 6 where this supplemental bar is shown attached to the rack.

In order to move the margin dog 26 positively out of engagement with the escapement wheel at the first operation of the dog rocker, said dog rocker is provided with an

adjustable screw 42 having its end lying just behind an ear 43 bent down from the dog 26. When the parts are in the position shown in Fig. 3 the screw 42 is in contact or nearly so with the ear 43 and when the dog rocker is moved toward the front of the machine by the depression of a key, said screw pushes the margin dog positively out of engagement with the wheel. As the carriage then begins to step toward the operator's left the friction of the shoe 37 on the rack 2 will maintain the dog in its inoperative position during the operation of writing and until said rack is again raised or until the carriage is moved toward the operator's right.

At a suitable distance forward of the pivot 28 the base plate 30 is bent upward to form a bracket 44 which is forked at its upper end, the shorter fork 45 lying beneath the arm 34 and serving to prevent accidental depression of said arm far enough to injure it. The other branch 46 of this bracket 44 is elongated and serves as a stop to limit the extent to which the margin dog can move away from the escapement wheel. The escapement wheel itself, as well as the screw 42, can limit the motion of these parts in the opposite direction.

The motion of the detent dog 27 is limited in both directions by an ear 47 bent downward therefrom into a notch 48 consisting of the space between two arms 50 of the base bracket 30. This dog has an abrupt end adapted to come into holding engagement with the tooth of the escapement wheel as shown in the drawings, and it also has an inclined part 49 on which the oncoming tooth of the wheel has a cam action, and which also itself has a cam action on the tooth of the wheel. If at the end of a line or in some other way the dog 21 has gotten in between two of the teeth of the escapement wheel in the manner above described and said escapement wheel assumes some intermediate position where the inclined part 49 of the detent dog is pressed against one of the teeth of said wheel, said inclined part tends to cam the wheel in a direction the reverse of its ordinary direction of motion until such reverse motion of the wheel is arrested by the next tooth thereof striking against the end of the dog, thus enabling the margin dog 26 to move into engagement with said tooth.

It will be perceived that I have mounted the entire margin controlling mechanism including the margin dog 26, the detent dog 27, and the spring 35 for controlling said dog all on the base 30, and that the stop for arresting the motion of the margin dog consists of an ear 46 bent up from said base. This entire piece of mechanism is thus made as a unit that can be put onto the machine and taken off as an entirety and which can

be adjusted as an entirety with relation to the escapement wheel, such adjustment being permitted by the slots through which the securing screws 31 pass. It will also be 5 perceived that both the detent dog and the margin dog have long pivots and that they are both controlled by a single spring.

There are advantages in having the margin dog and the detent both engage the same 10 tooth of the escapement wheel and in having them engage the same tooth of said wheel that is controlled by the feed dogs 20 and 21. This is partly due to the improved accuracy due to having everything that controls the escapement wheel engage at the same point, but also to the fact that different typewriting machines sometimes have different letter spacing, as for example twelve letters to the inch, and ten letters 20 to the inch, and other spacings are also provided for. These differences in spacing are brought about by employing escapement wheels with different numbers of teeth. The wheel shown in the drawings has twelve teeth; another wheel might have ten teeth, and so on; and if the margin dog and detent do not engage the same tooth of the escapement wheel as the feed dogs, then these parts would have to be made differently for different machines on account of the different spacing of the teeth.

Various changes can be made in the details of construction and arrangement without departing from my invention.

35 What I claim as new and desire to secure by Letters Patent, is:

1. In a typewriting machine and in carriage controlling mechanism, the combination with an escapement wheel, of a two-armed margin dog, one arm adapted to engage the escapement wheel and the other provided with a shoe having a spring shank, and a guard mounted on said shank to prevent improper bending.

45 2. In a typewriting machine and in carriage controlling mechanism, the combination with an escapement wheel, of a two-armed margin dog, one arm adapted to engage the escapement wheel and the other provided with a shoe having an inclined spring shank bendable toward said arm, and an overlying guard having an inclined lip to prevent improper bending of said shank.

55 3. In a typewriting machine and in carriage controlling mechanism, the combination with an escapement wheel, of a margin dog and a detent dog having a common pivot and both said dogs having yoke portions at said pivot, the yoke portion of one dog being arranged within the yoke portion of the other dog.

4. In a typewriting machine and in carriage controlling mechanism, the combina-

tion with an escapement wheel, of a margin 65 dog comprising two arms at substantially right angles to each other and having a junction yoke, and a detent dog also having a yoke fitted within the yoke of the margin dog, both of said yokes being pivoted.

5. In a typewriting machine and in carriage controlling mechanism, the combination with an escapement wheel, of a margin dog comprising two arms at substantially right angles to each other and having a junction yoke, a detent dog also having a yoke fitted within the yoke of the margin dog, both of said yokes having a common pivot, and a spring common to said margin dog and said detent dog.

6. In a typewriting machine and in carriage controlling mechanism, the combination with an escapement wheel, of a margin dog comprising two arms, a detent dog, a common pivot for both said dogs, and a 85 coiled spring around said pivot common to both dogs, one end of the spring pressing against the detent dog and the other end of the spring pressing against the margin dog.

7. In a typewriting machine and in carriage controlling mechanism, the combination with an escapement wheel, of a margin dog and a detent for engagement with said wheel, said margin dog and detent being pivoted to a stationary part of the machine 95 on a common pivot.

8. In a typewriting machine and in carriage controlling mechanism, the combination with an escapement wheel, of a margin dog and a detent pivoted on a common pivot, 100 and a single spring for drawing said margin dog and detent into engagement with said wheel.

9. In a typewriting machine and in carriage controlling mechanism, the combination with an escapement wheel, of a margin 105 dog and a detent engaging said wheel from opposite faces thereof, and a single spring for drawing said margin dog and detent into engagement with said wheel.

10. In a typewriting machine and in carriage controlling mechanism, the combination with an escapement wheel, of a margin dog, and a detent for preventing backward rotation of said wheel, said margin dog and 115 detent both engaging the same tooth of said wheel.

11. In a typewriting machine and in carriage controlling mechanism, the combination with an escapement wheel and a feed 120 dog, of a margin dog, and a detent for preventing backward rotation of said wheel, both said margin dog and said detent engaging the same tooth of said wheel as said feed dog.

12. In a typewriting machine and in carriage controlling mechanism, the combination with an escapement wheel and a feed

- dog, of a margin dog, and a detent for preventing backward rotation of said wheel, said margin dog and said detent both being mounted on a stationary part of the machine and both engaging the same tooth of said wheel as said feed dog.
13. In a typewriting machine and in carriage controlling mechanism, the combination with an escapement wheel and a feed dog, of a detent dog for preventing backward rotation of said wheel, said dog being pivoted on a stationary part to swing in and out transversely of said wheel and engaging the same tooth of said wheel as said feed dog.
14. In a typewriting machine and in carriage controlling mechanism, the combination with an escapement wheel, and its feed dogs, of a margin dog and a detent both engaging the same tooth of said wheel as said feed dogs, and one engaging said wheel from the back and the other from the front thereof.
15. In a typewriting machine and in carriage controlling mechanism, the combination with an escapement wheel and its feed dogs, of a margin dog and a detent pivoted on a common pivot, a single spring for drawing said margin dog and said detent into engagement with said wheel, and means normally restraining said margin dog from engagement with said wheel.
16. In a typewriting machine and in carriage controlling mechanism, the combination with an escapement wheel and its feed dogs, said feed dogs engaging the bottom tooth of said wheel, of a detent pivoted to a stationary part of the machine and lying horizontally and engaging the said bottom tooth to retain said wheel against backward rotation.
17. In a typewriting machine and in carriage controlling mechanism, the combination with an escapement wheel and its vibratory feed dogs, of a base plate detachably and adjustably mounted on a stationary part of the machine, a pivot on said base plate, and a margin dog and a detent both mounted on said pivot.
18. In a typewriting machine and in carriage controlling mechanism, the combination with an escapement wheel and its vibratory feed dogs, of a base plate detachably and adjustably mounted on a stationary part of the machine, a pivot on said base plate, a margin dog and a detent both mounted on said pivot, and a spring coiled about said pivot and controlling both said margin dog and said detent.
19. In a typewriting machine and in carriage controlling mechanism, the combination with an escapement wheel, of a dog for engagement with said wheel, a base plate mounted on a stationary part of the ma-
- chine and to which said dog is pivoted, and an ear bent up from said base plate and having one part thereof in position to prevent bending of an arm of said dog, and another part thereof constituting a stop to limit the motion of said dog about its pivot.
20. In a typewriting machine and in carriage controlling mechanism, the combination with a releasable feed rack and an escapement wheel, of a margin dog having one arm for engagement with said wheel and another arm having frictional connection with said rack, a base plate to which said dog is pivoted, and an ear bent up from said base plate and having one part thereof lying beneath the second mentioned arm of said dog to prevent bending of said arm and said ear having also a finger to act as a stop to limit the motion of said dog about its pivot.
21. In a typewriting machine and in carriage controlling mechanism, the combination with a releasable feed rack and an escapement wheel, of a margin dog for engagement with said wheel, a spring shoe on said margin dog for frictional contact with said rack, and a guard on said dog to control the point of flexure of said spring shoe.
22. In a typewriting machine and in carriage controlling mechanism, the combination with a releasable feed rack and an escapement wheel, of a margin dog for engagement with said wheel, a spring shoe on said margin dog for frictional contact with said rack, and a guard on said dog to control the point of flexure of said spring shoe, said shoe lying between said guard and an arm of said dog, the three parts being detachably secured together by screws and said guard preventing said shoe from having its point of flexure at a screw hole.
23. In a typewriting machine and in carriage controlling mechanism, the combination of an escapement wheel whose teeth are made with parallel back and front portions, feed dogs co-operating with the ends of said teeth, and a detent lying tangentially of said wheel and pivoted to the fixed framework of the machine and arranged to swing laterally into and out of position to engage one of said parallel side portions of each of said teeth.
24. In a typewriting machine and in carriage controlling mechanism, the combination with an escapement wheel, of a detent dog arranged to swing in and out of said wheel transversely to the wheel, said dog having a face for engagement with the backs of the teeth of the wheel to prevent backward rotation of the wheel and said dog having also an inclined part whereby the dog is cammed aside by each passing tooth of the wheel.
25. In a typewriting machine and in car-

riage controlling mechanism, the combination with a carriage escapement wheel and coöperating feed dogs, of an adjustable support, and a margin dog and a detent mounted on said support.

26. In a typewriting machine and in carriage controlling mechanism, the combination with a carriage escapement wheel and coöperating feed dogs, of an adjustable support, and a margin dog and a detent mounted on said support.

ed on said support and both engaging the same tooth of said wheel.

Signed at the borough of Manhattan, city of New York, in the county of New York and State of New York this 3rd day of 15 April, A. D. 1919.

OSCAR WOODWARD.
